UNITED STATES PATENT OFFICE.

JOSEPH HALL, OF LEEDS, ENGLAND.

DESIGN FOR A FINISHING-ROLL FOR LEATHER MACHINERY.

SPECIFICATION forming part of Design No. 27,760, dated October 19, 1897.

Application filed July 30, 1897. Serial No. 646,561. Term of patent 14 years.

To all whom it may concern:

Be it known that I, JOSEPH HALL, a subject of the Queen of Great Britain, residing at Leeds, in the county of York, England, have 5 invented and produced a new and original Design for Finishing Rolls or Cylinders for Hide, Skin, and Leather Machinery, of which the following is a specification, reference being had to the accompanying drawings, forming 10 part hereof, in which—

Figure 1 is a front elevational view of a roll or cylinder, showing my new design. Fig. 2 is a plan view of the periphery of the roll or cylinder projected upon a flat surface, and

15 Fig. 3 is a diagram illustrating the angular arrangement of the blades or vanes upon the periphery of the roll or cylinder.

As illustrated in the drawings, the leading feature of my design consists of two or more series of short blades or vanes *b, c, d, e, and f*, projecting at varying angles from a series of abutting oppositely-arranged helical main

blades *a a*, the short blades or vanes *b, c, d, e, and f* being also oppositely arranged in series and meeting at about the center of the 25 cylinder or roll in angular abutments *b', c', d', e', and f'*, falling below the point *a'* of abuttal of the long blades *a*. Upon the rounded surface of the periphery of the roll or cylinder the short blades and long blades present 30 a curved appearance, as illustrated in Fig. 1.

Having thus described my invention, what I claim as new, and desire to secure by Letters Patent, is—

The design for a finishing roll or cylinder 35 as herein shown and described.

In testimony whereof I have hereunto set my signature in the presence of two subscribing witnesses.

JOSEPH HALL.
